DANIEL DENSMORE, OF RED WING, MINNESOTA.

Design No. 4,668, dated February 21, 1871.

DESIGN FOR CLOTHES-LINE REEL-IRONS.

The Schedule referred to in these Letters Patent and making part of the same.

To all whom it may concern:

Be it known that I, DANIEL DENSMORE, of Red Wing, in the county of Goodhue and State of Minnesota, have invented a new and original Design for Clothes-Line Reel-Irons; and I do hereby declare that the following is a full, clear, and exact description of the same, reference being had to the annexed drawing making a part of this specification and to the letters and figures of reference marked thereon.

Figure 1 of the drawing is three views in perspective.

The nature of my design is fully represented in the

accompanying photographic illustration, to which reference is made.

I claim as my invention—

The design for clothes-line reel-irons, as shown.

In testimony that I claim the above I have hereunto subscribed my name in the presence of two witnesses.

DANIEL DENSMORE.
